UNITED STATES PATENT OFFICE.

FRANK A. WONDRA, OF SCHENECTADY, NEW YORK.

TORPEDO-LAUNCHING APPARATUS FOR FLYING-MACHINES.

1,302,747.

Specification of Letters Patent.

Patented May 6, 1919.

Application filed May 3, 1916, Serial No. 95,222.

Renewed November 19, 1917, Serial No. 202,872.

To all whom it may concern:

Be it known that I, FRANK A. WONDRA, a citizen of the United States, residing at Schenectady, county of Schenectady, State of New York, have invented new and useful Torpedo-Launching Apparatus for Flying-Machines.

My invention relates to improvements in marine automobile torpedo launching apparatus for flying machines, in which the torpedoes are carried through the air and can be started upon the flying machine and launched therefrom into the water with a high degree of accuracy in a predetermined course, all during the flight.

Another object of my improvements is to provide means to avoid premature launching of the torpedoes.

I attain these objects by the mechanism illustrated in the accompanying drawings in which Figure 1 is a side view of the apparatus designed for two torpedoes; Fig. 2 is a transverse sectional view on line A. A. of Fig. 1, looking in direction of the arrows; Fig. 3 is a transverse sectional view on line B. B. of Fig. 1 looking in the same direction; Fig. 4 is an enlarged view of the locking bar of the upper torpedo-holder, showing the safety bolt and Fig. 5 is an enlarged view of the locking bar of the lower torpedo-holder.

The torpedoes E and E^a are shown in dash and dot lines.

The longitudinal steel tubes C are built into the flying machine's lower framework and support the apparatus with the torpedoes.

Upon the tubes are fastened the upright frames 1, 1^a and 2, 2^a which fit the diameters of the respective torpedoes. To the frames 1 and 2 are riveted the hoods 3 and 4 which are of sheet metal and fit the upper half of the torpedo-head with an enlargement for the protection of the strikers of the torpedoes.

The frames 1^a and 2^a have similar hoods 5 and 5^a which fit the upper half of the torpedo tail and have openings 6 and 6^a for the starting latches D and D^a of the torpedoes.

These front and rear hoods hold the torpedo in the upper half tight and prevent any longitudinal shifting of the same.

To the frames 1 and 1^a are pivoted the crank levers 7 upon the bolts 8, and the

levers 9 upon the bolts 10 movably secured; 55 both levers are connected together by the links 11.

To the frames 2 and 2^a are the crank levers 12 upon the bolts 13 and the levers 14 upon the bolts 15 movably mounted and are connected together by the links 16.

The motion of the different lever arms is shown in dash and dot lines in the drawings.

In normal position the outer lever arms 65 of the crank levers 7 and 12 form with the connecting links 11 and 16 respectively, a straight line.

The inward motion of the connecting links is limited by the pins 17 and 18.

The inner lever arms of the levers 7 and 12 have antifriction rollers 19 and 20 which slide in the curved grooves 21 and 22 of the locking bars.

Each locking bar has two sets of grooves, 75 one set to each frame and the center ribs 23 and 24 give the necessary strength and form the guide supports for the bars, the guide-way parts of which are machined into each frame.

The frames 1 and 1^a have extending arms with hubs for the spars 25 which connect both the grooved barpieces together; the spars 25 are slidably supported by each frame.

The connecting rod 26 which is located in the center above the upper torpedo, connects the grooved barpieces located in front of the frames 2 and 2^a together and form thus the locking bar for the upper torpedo- 90 holder.

The locking bars have hand-grips 27 and 28 respectively. The grip 27 has a segmental extension 40 which is adapted to turn over the starting latch D, of the torpedo 95 when the locking bar is pulled but when pushed, the hinged extension 40 passes over the latch D without pressing it.

Upon the rod 26 is fastened a bracket 29^a with a segment 41 hinged on so as to engage 100 the latch D^a of the upper torpedo when pulled.

The connection spar 29 makes the frames 2 and 2^a more rigid.

The inner lever arms of the levers 9 and 105 14 support movably the glideshoes 30 and 30^a which fit the respective torpedo, and press the same against the hoods of the frames.

For a large size torpedo, another frame similar to the frame 1^a may be added and placed about in the center of gravity of the torpedo but the hood would be omitted.

- 5 To prevent premature launching of the torpedoes there is a pin 31 projecting into the connection spar 25 and is lifted therefrom by the lever 32 the fulcrum of which is supported by the frame 1^a. The drawrod 33 is supported by the bracket 34 upon the connection spar 25.

- For the upper torpedo there is the pin 35 projecting into the rib 24 of the locking bar and lever 36 with drawrod 37 which has 15 a guide 38 built into the framework of the flying machine. The fulcrum of the crank lever 36 is supported by the frame 2^a.

- The grooves 21 and 22 of the locking bars are partly straight, take then a turn of 90° 20 (see Figs. 4 and 5) and end at 39 and 39^a respectively forming thus openings through which the rollers 19 and 20 swing out.

- This launching apparatus is adaptable to any kind of flying machines or aerial vehicles, can be designed to hold one or more 25 torpedoes and is operated as follows:

The locking bar is pulled out until the rollers 20 slide through the opening 39^a whereby the glideshoes 30^a hang free downward. The torpedo E^a is then hoisted by a suitable means (not shown) between the glideshoes against the hoods 3 and 5^a with the starting latch D^a on the upper side. Then the cranklevers 12 are brought through 35 the openings 39^a into the grooves 22 of the locking bar which is pushed forward until the rollers reach the ends of the straight parts of the grooves. This brings the glideshoes against the lower half of the torpedo 40 and the links 16 with the outer arms of the levers 12 into a straight line.

The stresses resulting from the weight of the torpedo as it presses against the glideshoes are now concentrated in the bolts 13 45 whereby the rollers 20 are unloaded. The pin 35 is then pushed in a corresponding hole in the locking bar and the torpedo is now firmly clutched in the launching apparatus.

50 The lower torpedo E is brought into its position the same way as the E^a but with the corresponding levers and locking bar.

In order to launch the torpedo the flying machine takes the course in which the torpedo should be fired and descends as low 55 as necessary to save the torpedo from breaking when it falls into water.

The lower torpedo E must be launched first. It is assumed that the operator seat 60 is behind the tail of the lower torpedo. However, the connecting spars and drawrods can be extended right to the aviator seat and operated therefrom.

By drawing the drawrod 33 the pin 31 is 65 withdrawn from the connection spar 25 and

then the operator pulls on the handgrip 27 whereby the segment 40 turns over the starting latch D of the torpedo, setting thereby the torpedo machinery into motion.

At the same time the locking bar has been 70 drawn out so far that the rollers 19 begin to follow the circular turn of the grooves 21; this swings the links 11 outward and the weight of the torpedo acting upon the glideshoes 30 helps to draw the rollers 19 75 through the openings 39 whereby all the levers and links are freed and the torpedo slides upon the glideshoes 30 with its machinery working, downward into water.

When the lower torpedo has been launched 80 then the upper one can be released the same way by pulling the drawrod 37 and then on the handgrip 28.

It is advisable to carry two torpedoes at the same time wherever a protective obstruction 85 is found before the ultimate target.

As the speed of the torpedo in water is lower than the speed of the flying machine, the upper torpedo although being launched later, will reach the obstruction first and 90 cleaning the same away by the explosion, making thereby free passage for the lower torpedo which has been launched first, for its ultimate effect.

The apparatus as here described can also 95 be adjusted to hold and eject aerial torpedoes or shells from aerial vehicles while in flight.

In accordance with the provisions of the patent statutes, I have herein set forth the 100 principles of my invention and described the best embodiment thereof at present known to me. While, however, the invention extends to the particular apparatus described and its various specific features and details 105 and novel combinations and arrangements of parts, it is not confined thereto, but can be otherwise carried out and embodied.

What I claim as new and desire to secure by Letters Patent of the United States, is— 110

1. In an apparatus for launching of marine automobile torpedoes from flying machines the combination of a plurality of upright frames spaced apart longitudinally and fastened upon the flying machine body; 115 the hoods adapted to engage the upper half of the head and tail of the torpedo, fastened to the frames; a pair of crank levers mounted above said hoods upon each frame and adapted to swing transversely to the axis of the torpedo and having at the inner lever arms each a roller; a locking bar mounted above said hoods upon said frames parallel to the axis of the torpedo and having grooves adapted to engage and release said rollers; 120 a pair of levers mounted upon each frame approximately in line with the lower contour of the torpedo, glideshoes movably mounted upon the inner arms of said levers and adapted to hold the torpedo against 125

said hoods; connection links between said levers and said crank levers and means fastened upon said locking bar for actuating the starting latch of the torpedo.

- 5 2. In a torpedo carrying and ejecting apparatus for aerial vehicles in combination a plurality of upright frames spaced longitudinally apart and fastened to the body of the aerial vehicle; hoods fastened to said frames and adapted to engage the head and tail of the torpedo; a plurality of bell cranks mounted upon each frame above the torpedo and having on the inner lever arms each a roller; a locking bar slidably mounted upon said frames parallel to the axis of the torpedo and having grooves adapted to engage and release said rollers; a plurality of levers mounted upon the lower portion of said frames and having at the inner lever arms each a movable glideshoe; connecting links between said levers and said bellcranks.

3. In a torpedo carrying and ejecting apparatus for aerial machines a plurality of upright frames mounted upon the aerial machine and adapted to support the torpedo at the head and tail, a locking-bar slidably mounted upon said frames parallel to the torpedo and having grooves parallel to the torpedo axis with openings in said grooves 25 at right angles to the longitudinal axis of the torpedo, a plurality of members movably mounted upon said frames and having each a movable glideshoe pressing against the torpedo in combination with means engaging said members with said locking-bar and means disengaging said members from said locking-bar.

4. In combination with an aerial machine, a torpedo of the submarine automobile type having an external starting latch, a plurality of upright frames fastened to the aerial machine and having hoods adapted to engage the upper part of the head and tail of the torpedo, a plurality of levers pivotally mounted upon said frames and carrying each a movable glideshoe adapted to hold the torpedo against said hoods; means for retaining said levers and glideshoes against the torpedo and means for releasing said re-

taining means and simultaneously operating the starting latch of the torpedo.

5. In a torpedo carrying and releasing apparatus for aerial machines a plurality of upright frames spaced longitudinally apart and fastened to the aerial machine, hoods 55 fastened to said frames and adapted to engage the head and tail of the torpedo, one of said hoods having an opening for the torpedo starting device, a plurality of bellcranks pivotally mounted upon each frame above the torpedo and having on the inner lever arms each a roller, a locking-bar slidably mounted upon said frames and having grooves adapted to engage and release said rollers, means for holding said locking-bar 60 stationary in said frames, a plurality of levers pivotally mounted upon the lower portion of said frames and having at the inner lever arms each a glideshoe, connecting links between said levers and said bellcranks and 65 means for actuating the starting device of the torpedo.

6. In an apparatus for launching of marine automobile torpedoes from aerial machines in combination a plurality of upright 75 frames spaced apart and fastened to the aerial machine, hoods upon said frames adapted to engage the head and tail of the torpedo, a plurality of bellcranks pivotally mounted upon each frame and having on 80 the inner lever arms each a roller, locking-bars slidably mounted upon said frames and having grooves adapted to engage and release said rollers, a plurality of levers pivotally mounted upon the lower portion of 85 said frames and having at the inner lever-arms each a movable glideshoe, connecting links between said levers and said bellcranks, means for actuating the starting device of the torpedo and means for disengaging said locking-bar from said frames.

In witness whereof, I have hereunto set my hand this 2d day of May, 1916.
